UNITED STATES PATENT OFFICE.

MAHLON E. LAYNE, OF HOUSTON, TEXAS

MOVABLE POWER UNIT.

Application filed September 5, 1922. Serial No. 586,346.

To all whom it may concern:

Be it known that I, MAHLON E. LAYNE, a citizen of the United States, residing at Houston, in the county of Harris and State 5 of Texas, have invented a new and useful Movable Power Unit, of which the following is a specification.

This invention relates to a movable power unit and is particularly directed to a driving motor laterally movable to or from a position of operative connection with a driven mechanism.

An object of the invention is to provide a power unit adapted to be operatively connected with a driven mechanism and associated with means for elevating said unit and laterally translating it away from said mechanism.

Another object is to provide lateral tracks 20 upon which wheeled trucks travel, and to provide means between the trucks and the power unit, operative in one instance to elevate and support the power unit for lateral translation, and in another instance to lower 25 the power unit to position of use free from support by the trucks.

A further object is to provide a vertical driving motor adapted to be directly connected to the driven shaft of a centrifugal 30 deep well pump and having associated wheeled trucks adapted to travel laterally upon track members, and to provide jack-screws or lifting means between the motor and said trucks whereby the motor and its 35 support or frame may be elevated and supported upon the trucks for lateral translation away from the well to afford access to the well mechanism, or to be lowered to position of use free from support by the trucks.

Another object is to provide a pump-head 40 structure including track members upon which a motor supporting and elevating means is adapted to travel in a lateral translation of the motor to and from the pump-head.

Various other objects and advantages will 45 be more fully apparent from the following description of the accompanying drawings which form a part of this disclosure and which illustrate a preferred form of embodiment of the invention.

Of the drawings:

Figure 1 is an elevation of the power unit of the present invention associated with a deep-well pumping mechanism. 55

Fig. 2 is a plan section on line 2—2 of Fig. 1.

Fig. 3 is a transverse section showing the power unit in position of use.

Fig. 4 is a plan view of one of the truck 60 members.

Fig. 5 is a detail section on line 5—5 of Fig. 4.

In the drawings is illustrated a vertical electric motor as the power unit utilized in 65 this instance to drive a centrifugal deep well pump and adapted to be laterally translated to and from a position of use over the pump head, but it is to be understood that this is only illustrative of one of the various 70 embodiments to which the structure of the present invention is susceptible, and that other specific types of motors may be employed if desirable.

In the specific embodiment shown, 1 designates the well casing in which is positioned the well tubing 2 leading down into the well to a suitable centrifugal pump (not shown) and communicating with a well head 3 having a discharge pipe 4. The pump shaft 5 extends upwardly through the pump head 3 and carries one member of a separable shaft coupling which is indicated generally by the reference character 6 and which may be of any desirable or well known type. The 75 pump head has a table plate 7 upon which the power unit rests when in position of use.

This general form of well mechanism is now so well known in the art that further 80 detailed description thereof would be superfluous.

In the present instance the structure for supporting the pump head 3 includes two parallel beams 8 which extend upon opposite 85 sides of said head and which also serve as track members upon which the power unit is translated. These beams 8 are preferable channel beams, their medial web being secured to the pump head 3 by bolts 9 and 100 their opposite ends resting upon and secured to transverse beams 10 embedded in concrete.

This provides a pump head structure supported by opposed parallel track members and contributes to a simple, cheap and durable means of supporting the pump. However, it will be evident that instead of bolting the tracks to the pump head by the bolts 9, the pump head may rest directly upon the foundation, leaving the tracks as separate individual members.

10 The power unit in the present embodiment of the invention, comprises a vertical electric motor 11 superposed upon a motor stand 12 which is cut away as at 15 so that as the motor is translated to position over the pump head 3, the pump shaft 5 and other parts of the pump head may pass through said side opening 15 to a position within the motor stand.

15 The means for elevating and translating the motor, consists of duplicate wheeled trucks, indicated generally by the reference character 16, and adapted to travel along the top surfaces of the beams 8. Each truck consists of opposed members 17 joined together by an intermediate angle iron 18, and supporting wheels or rollers 19 journaled in the forked ends of the members 17. Guide fingers 20 are secured to the trucks and engage over the outer top edge of the beams 8 to maintain the trucks in proper alignment upon the tracks. Each member 17 is provided with a recess 21 and projecting outwardly from the base ring 14 of the motor stand 12 are bosses 22 carrying vertically disposed jack-screws 23, said jack-screws having a screw threaded engagement in the respective bosses and extending downwardly into the recesses 21 of the trucks so that upon turning the jack-screws 23 in one direction the motor unit will be elevated and supported upon the trucks, and upon turning said jack-screws in the reverse direction the motor unit will be lowered.

20 With the motor unit positioned over the pump head 3 and lowered into the table plate 7, it will be secured in place by suitable bolts passing through orifices 25 in the base ring 14 of the motor stand 12 and engaging into screw-threaded orifices 26 in said plate.

25 When it is desired to move the motor unit from over the pump head, the motor stand is first disconnected from the table plate 7 and the jack-screws 23 manipulated to elevate the motor unit and support it upon the trucks. The entire motor unit may then be drawn laterally along the tracks and away from over the pump head, suitable stops 27 being associated with the tracks to limit the travel of the trucks. To replace the motor unit this operation is reversed, that is, the trucks carrying the motor unit are moved to a position to bring the motor directly over the pump head and the jack-screws then manipulated to lower the motor unit upon the table plate 7 free from support by the trucks,

and the motor stand bolted to the table plate.

The trucks may then be removed until again needed or may be left in place if desired.

20 Further, if desired the motor stand 12 may be cut away opposite the opening 15, as indicated in dotted lines in Fig. 2, so that the power unit may be moved in either direction to and from the pump head.

25 It will be evident that with a power unit in which the supporting base or stand has a side opening, the entire power unit may be moved laterally from and to the pump head and over such parts as project above the pump head, without elevating the power unit more than just enough to transfer the weight of the power unit from the pump head to the trucks.

30 The mechanism above described provides a strong, durable and simple structure capable of fulfilling all of the objects primarily stated, and while embodying a preferred form of structure it is only intended to present one of the many forms of which the invention is susceptible, therefore, it is to be understood that I do not wish to limit the invention beyond the scope of the following claims.

35 I claim:

1. A power unit adapted to be secured in a position of operative connection with a driven mechanism, and means for elevating said power unit and translating it laterally away from said mechanism, said means including laterally extended tracks, truck members upon said track, and elevating means operative in one instance to elevate the power unit from position of use and support it upon the trucks for lateral translation, and in another instance to lower the power unit to position of use free from support by said trucks.

2. A power unit adapted to be secured in a position of operative connection with a driven mechanism, and means for elevating said power unit and translating it laterally away from said mechanism, said means including laterally extended tracks, truck members upon said tracks, and jack-screws between the power unit and the trucks operative in one instance to elevate and support the power unit upon the trucks for lateral translation, and in another instance to lower the power unit to position of use free from support by the trucks.

3. A power unit including a vertical motor adapted to be secured in a position of operative connection over a driven mechanism, and means for elevating said motor and translating it laterally to afford access to said mechanism, said means including laterally extended tracks, wheeled trucks adapted to travel on said tracks, and elevating means between the motor and trucks

operative in one instance to elevate the motor from the driven mechanism and support it upon the trucks for lateral translation, and in another instance to lower the motor to position of use free from support by said trucks.

4. A power unit including a vertical motor adapted to be secured in a position of operative connection over a driven mechanism, and means for elevating the motor and translating it laterally to afford access to said mechanism, said means including laterally extended tracks, wheeled trucks adapted to travel on said tracks, and jack-screws between the motor and trucks operative in one instance to devote and support the motor upon the trucks for lateral translation, and in another instance to lower the motor to position of use free from support by said trucks.

5. A power unit including a vertical motor carried by a motor stand adapted to be secured in a position of operative connection over a driven mechanism, and means for elevating said power unit and translating it laterally to afford access to said mechanism, said means comprising laterally extended tracks, wheeled trucks adapted to travel on said tracks, and jack-screws having a screw-threaded engagement in the motor stand and engaging the adjacent trucks, said screws being operative in one instance to elevate and support the power unit upon the trucks for lateral translation, and in another instance to lower said unit to position of use free from support by said trucks.

6. A power unit comprising a pump-head structure including parallel supporting track members, a motor adapted to be operatively positioned upon the pump head,

and means for elevating and translating the motor away from the pump-head, said means including wheeled trucks adapted to travel upon the track members, and elevating means between the trucks and the motor operative in one instance to elevate and support the motor upon the trucks for lateral translation, and in another instance to lower the motor to position of use free from support by said trucks.

7. A power unit for a well mechanism having an upwardly projecting driven shaft, said power unit having a supporting frame provided with a side opening extending upwardly from its lower supporting surface, and adapted to be shifted horizontally to encase said shaft while said surface is below the upper end of the shaft.

8. A power unit for a well mechanism having an upwardly projecting driven shaft, said power unit having a supporting frame provided with a side opening extending upwardly from its lower supporting surface, and adapted to be shifted horizontally to encase said shaft while said surface is below the upper end of the shaft, and means for elevating and translating the power unit, said means including laterally extending tracks, trucks members upon said tracks, and elevating means operative in one instance to elevate the power unit from position of use and support it upon the trucks for horizontal translation, and in another instance to lower the power unit to position of use free from support by said trucks.

Signed at Memphis, Tenn., this 20 day of June, 1922.

MAHLON E. LAYNE.
